(57) **CLAIM**

The ornamental design for a protective case for a watch, as shown and described.

DESCRIPTION

FIG. 1 is a front, right and top perspective view of a protective case for a watch, showing my new design; FIG. 2 is a rear, left and bottom perspective view thereof; FIG. 3 is a front view thereof; FIG. 4 is a rear view thereof; FIG. 5 is a left side view thereof; FIG. 6 is a right side view thereof; FIG. 7 is a top plan view thereof; FIG. 8 is a bottom plan view thereof; and, FIG. 9 is an enlarged view of portion of FIG. 1 thereof. The dot-dash broken lines depict the boundaries of the enlargements that form no part of the claimed design.
